UNITED STATES PATENT OFFICE.

GUION THOMPSON, OF DULUTH, MINNESOTA, ASSIGNOR TO THE THOMPSON SAFETY APPLIANCE COMPANY, A CORPORATION OF NEW JERSEY.

MEANS FOR ESTABLISHING ELECTRIC CIRCUITS.

SPECIFICATION forming part of Letters Patent No. 788,563, dated May 2, 1905.

Application filed July 1, 1902. Serial No. 113,946.

To all whom it may concern:

Be it known that I, GUION THOMPSON, a citizen of the United States, residing at Duluth, in the county of St. Louis and State of Minnesota, have invented new and useful Means for Establishing Electric Circuits, of which the following is a specification.

My invention relates to means for establishing an electric circuit, and has for its object the provision of means whereby such circuit may be established from a battery or other source of electricity carried by a moving conveyance through stationary conductors of electricity located upon the route of said conveyance.

It comprises the combination of a source of electricity carried by a movable conveyance, electricity-conducting means connected to one of the poles of said source and adapted to contact with stationary electricity-conducting means located upon the route of said conveyance, electricity-conducting means connected to the other pole of said source and adapted to contact with a second stationary conductor of electricity located upon said route, a series of intermediate conductors of electricity located upon said route and extending from one of said stationary conductors to the other and forming a normally operative conductor from said first to said second stationary conductor adapted to be interrupted by the movement of the support of one of the elements of said series.

It also consists of certain other constructions, combinations, and arrangement of parts, as will be hereinafter described.

In the drawings, Figure 1 is a diagram of the portions of said circuit which are anchored upon the route of said conveyance. Fig. 2 is a diagram of a movable conveyance upon said route and of the portions of said circuit carried thereby, showing in dotted lines a lamp-circuit which my invention may be made to interrupt. Fig. 3 is a detail of a modified construction of a part of said anchored portions.

In the drawings, A and A', respectively, represent the rails of a railway-track, and A³ is a short rail or contact external to the rails of

said track and preferably supported by a support d. Connected at one end to said external rail A³ and extending backward a suitable distance along said track is a conductor of electricity A⁵, provided at its opposite end with a contact e. Connected at one end to said rail A and extending therefrom to the vicinity of said contact e is a conductor of electricity A⁴, provided with a terminal contact e', adapted to electrically communicate with said contact e through the medium of a double intervening or bridging contact e², as shown in Fig. 1, or by any other suitable means, which contactual or communicating relation is adapted to be controlled by a position-governing means of any suitable construction, as an armature A⁶ of an electromagnet A⁷, anchored in any suitable manner on the bed of said track, to which armature said double contact e² is attached and by which it is adapted to be temporarily withdrawn from contact with said contacts e and e' when said armature is attracted toward said electromagnet or otherwise moved from its normal position. It is obvious, however, that said contact e' may within the scope of my invention be made to normally contact directly with said contact e, as shown in Fig. 3, under the control of such position-governing means by attaching either of said contacts e or e' to said means A⁶ in a position to contact with the other and relatively detached one of said contacts, or any other suitable construction may be employed which will effect equivalent relations between said conductors A⁴ and A⁵. The coil of said electromagnet A⁷ is included in a normally open circuit comprising a battery A⁸ or other source of electricity, the conductor A⁹, the normally closed circuit-breaker A¹⁰, the conductor A¹¹, the conductor A¹², the front stop A¹³, and the normally open circuit-closer or armature A⁶. B represents a locomotive or other conveyance adapted to move on said rails A and A', which conveyance carries a battery b' or other source of electricity, to the opposite poles of which are connected conductors of electricity, as at b² and b³, of any suitable material or construction and

normally so separated or insulated from each other as to be electrically non-intercommunicative, the conductor b^3 being adapted to contact, through the medium of the axle and 5 wheel of the conveyance, forming a conductual extension thereof, with the rail A, the conductor b^2 being adapted to contact directly or through a suitable terminal contact, as b^4 , with said external rail A³. Said conveyance also carries a magnet or energized 10 electromagnet H, which is adapted in passing said armature A⁶ to attract and operate the same, either directly or through the medium of said electromagnet A⁷, and is further 15 adapted when passing said circuit-breaker A¹⁰ to operate the same to open the circuit controlled thereby. Said battery b' may also be included in a normally closed circuit 20 including portions of said conductors b^2 and b^3 and a signal-lamp C. (Shown in dotted lines on said conveyance.) It is obvious also that said conductor A⁴ may, within the 25 scope of my invention, be attached to either one of said rails A or A', or, if desired, to a second external rail or contact similar to said rail A³, placed transversely or diagonally opposite to said rail A³, preferably forward of said armature A⁶, in which latter event the conductor b^3 may be constructed in a manner 30 similar to conductor b^2 and arranged to contact with such second external rail at the same time that said conductor b^2 contacts with said rail A³. It is regarded as one of the essential features of my invention that 35 the construction thereof shall be such that said means A⁶ may normally be operated by some operating means on the conveyance, directly or through intermediate means, to interrupt the electroconductual relation between 40 said contacts e and e' shortly before the conductors b^2 and b^3 have both contacted with their corresponding rail-contacts, which requirement is complied with, preferably, by leading said conductor A⁵ backward from 45 said external rail A³ and by placing said rail A³ forward of said governing means A⁶, as shown; but I do not desire to limit myself to such exact construction, since the same results may be attained by modified or extended 50 constructions within the spirit and scope of my said invention.

The operation of my said invention is as follows: When a conveyance so equipped passes from left to right along said route, the 55 road - bed equipment and the conveyance equipment being in working order, the magnet H directly or through the medium of the magnet A⁷ will first operate the armature A⁶ to close the circuit including said battery A⁸, by which the energy of said magnet A⁷ will 60 be maintained. The movement of said armature will suspend the conductive communication between the conductors A and A³. When, therefore, the conductors b^2 and 65 b^3 are subsequently brought into contempo-

normally contact, respectively, with conductors A³ and A, no current passes from said battery b' through said conductors A³ and A, and said lamp C remains lighted. If, however, said circuit including said battery A⁸ fails of operation, said armature A⁶ will be dropped as soon as passed by said magnet H and the conductive communication reestablished from conductor A to conductor A³, in which event when the conveyance brings said conductors b^2 and b^3 simultaneously into contact with said conductors A³ and A, respectively, the current from battery b' will be short-circuited from said lamp C, and the consequent extinction of the light thereof will give warning that the circuit including said battery A⁸ failed, which operation is regarded as of very great importance and may be characterized as a "fail-to-danger" construction as distinguished from a construction by which the failure of the assumed circuits will leave a safety-signal displayed in the cab of the engine.

The utilities of my invention are manifold, and one of them may be suggested by the fact that said magnet A⁷ when energized and continued in operation by the means described is adapted to operate additional means (not shown) carried by a following conveyance to warn the driver of such following conveyance of the presence of the preceding conveyance between the positions of the magnet A⁷ and the circuit-breaker A¹⁰. The failure of the circuit in which said magnet A⁷ is included would incapacitate said magnet for such service, and but for the fail-to-danger construction herein described the driver of said following conveyance, ignorant of the failure of the signal system, might continue to a collision with the preceding conveyance. It is obvious that my said invention may be modified or extended in minor details and that such contacts and conductors may be constructed in any suitable manner or of any suitable materials or supported by any suitable means or in any suitable manner and that any suitable source of electricity of any suitable construction may be substituted for said battery b', all within the scope of my said invention.

Having now described my said invention, what I claim, and desire to secure by Letters Patent, is—

1. The combination of a normally open electric circuit including a source of electricity, electromagnetic means and a normally open circuit-controlling contact; a partial circuit including a normally closed contact and a normally open contact; means governed by said electromagnetic means and adapted when operated thereby to close or maintain the closure of the first said normally open circuit-controlling contact; means governed by said electromagnetic means and adapted when operated thereby to open said

normally closed contact; a traveling bridging contact constituting a normally open electric circuit and including a source of electricity and adapted during passage to close for a brief period the normally open contact of said partial circuit, and an electrically-operated device governed by said normally open traveling circuit.

2. The combination of a normally open electric circuit including a source of electricity the coil of an electromagnet and a normally open circuit-controlling contact; a partial circuit, including a normally closed circuit-controlling contact and a normally open circuit-controlling contact; an armature for said electromagnet adapted when operated thereby to close the first said normally open contact; a traveling bridging

contact, constituting a normally open electric circuit and including a source of electricity and adapted during passage to close for a brief period the normally open contact of said partial circuit; a closed electric circuit of relatively high resistance including the last said source of electricity and a part of the said normally open traveling circuit, or traveling contact, and an electrically-operated signal device.

In testimony whereof I have signed this specification in the presence of two subscribing witnesses.

GUION THOMPSON.

In presence of—

FLOYD PRICE,
JAMES T. WATSON.
